 Eaton Manufacturing Company, Cleveland,
 Ohio, a corporation of Ohio

Application May 12, 1938, Serial No. 207,478

5 Claims. (Cl. 237—12.3)

This invention relates to vehicle heating systems and particularly concerns means for use in conjunction with hot water heaters for preventing undesirable noises resulting from gurgling of the water in said heaters.

The primary object of this invention is the provision of means in conjunction with hot water heaters for eliminating the gurgling noise which usually results due to circulation of water with aerated fluid through the radiator of the heating system.

Investigation as to the cause of this sound has established it to be made by air bubbles locked in the heating fluid that is circulated under pressure to the inlet tank of the heater radiator, and as the fluid emerges from the core passages into the outlet tank there is a rapid expansion in the reduced pressure area as the air separates from the water producing a gurgling sound as each air bubble is freed to the top of the outlet tank. Research directed toward the solution of this problem has established that the most practical way to cure this annoyance is to prevent any aerated fluid from being circulated through the heater core.

A further object of this invention is the provision of an air separating means for use in conjunction with a conventional hot water heater radiator of an automotive vehicle that substantially prevents any core resonance resulting from gurgling of the water during the operation of said heater.

A further object of this invention is the provision of means adaptable to conventional hot water heaters as used on ordinary motor vehicles that substantially prevents circulation of air through said heaters.

A still further object of this invention is to provide in combination with an automotive vehicle having an internal combustion engine, a water circulating system therefor, and a heating device deriving heat from said system for warming the passenger compartment of said vehicle, an air separating means adapted to be serially connected in the supply side of said heater and having an air by-pass pipe extending from the high point of said means to a source of suction in said water circulating system.

A still further object of this invention is the provision of an air separating means for use in conjunction with a hot water heater for the passenger compartment of an automotive vehicle, adapted to be serially connected to the inlet side of said heater, and having an air escape conduit in communication with the discharge side of said heater.

Other objects and advantageous features will become apparent when considered in conjunction with the following description and the accom-

panying drawing, wherein like numerals designate like parts in the several views.

Fig. 1 is an elevational view partly in section illustrating a heater core with supply and discharge pipes leading therefrom and incorporating the subject matter of this invention, and

Fig. 2 is a partly cut-away elevational view of the device of this invention removed from the heater circuit of Fig. 1, and

Fig. 3 is a top plan view of the cylindrical tank of Fig. 2, and

Fig. 4 is a longitudinal view through an engine compartment and a section of the passenger compartment of an automotive vehicle and heating device depicting one form of this invention joined in the heater circuit.

In Fig. 1 a conventional hot-water heater core 10 has tanks 11 and 12 at the ends thereof with which supply and discharge pipes 13 and 14 are connected, respectively. Adjacent the inlet tank 11 and in the supply pipe 13 a cylindrical tank 15 is serially connected. That is to say, inlet pipe 16 of cylindrical tank 15 is connected to supply pipe 13, and outlet pipe 17 of tank 15 is joined to supply pipe 13 ahead of the heater core. A centrally located conduit 20 on the upper axis of tank 15 preferably has its free end joined as at 21 to discharge pipe 14 and extends a short distance on the axis thereof to create an aspirator effect by the reduced flow area past its mouth. The operation of tank 15 is as follows:

Inlet pipe 16 is tangentially joined to tank 15 near the top portion of the cylindrical section and similarly outlet pipe 17 is tangentially joined to the tank adjacent the lower portion thereof, as best shown in Figs. 2 and 3. A cover member 19 of hemi-spherical shape is sealingly secured to the cylindrical portion of the tank, and axially located at the upper extremity of the cover member a pipe 20 of small bore relative to the inlet pipe 16, leads from the tank. Water enters the tank through inlet pipe 16, which is fed by the heater supply pipe 13, and being tangentially joined to the outer periphery of the tank a rotary motion is imparted to the fluid. The water having a greater specific gravity than the entrapped air will flow by centrifugal force to the outer regions of the tank and descend spirally toward the bottom of the tank, while the air being lighter than the water will tend to separate from the water and remain near the axis of the tank, and in the reduced pressure area existing in the tank will rise to the top portion of the tank where it will be vented through the by-pass tube 20. As shown in Fig. 1, this by-pass tube is shunted to the heater core discharge pipe 14 by means of a suitable fitting 21. It will be evident now that substantially air-free water will flow from the tank outlet pipe 17 to the supply pipe 13 and into the heater tank 11 and core 10. Further,

the fluid flow in discharge pipe 14 being restricted in area by the insertion of by-pass tube 20 shunted into the axial bore thereof will create an aspirator effect at the mouth of the tube and produce a suction in the tube tending to draw the free air from the air separating tank 15. The relative sizes of inlet pipe 16 and by-pass tube 20 and their respective locations effectively prevents any short-circuiting of the heating fluid around the core, by providing a low pressure exit for the air, for example, one embodiment of the invention uses a $\frac{1}{16}$ " inlet and outlet tank tubes and $\frac{1}{8}$ " air by-pass tube. Obviously the inlet tube 16 may enter the tank 15 parallel to the major axis thereof and tangential to the outer periphery of the tank so as to slow up the water flow as it enters the tank and increase the tendency of the air and water to separate before the water begins its centrifugal spirally downward path. This construction would only necessitate a right angle rotation downwardly of inlet pipe 16 as viewed in Fig. 2. In the previously described construction the air by-pass tube has been described as being joined to the discharge pipe of the heater merely because it provided a source of lower pressure or suction to effect the withdrawal of air from the air separating tank 15. Obviously the air by-pass tube may be joined with any other convenient source of suction existing in the engine circulating system, an example of which is shown in the following description.

In Fig. 4 a hot-water heating device 23 is shown connected to the engine circulating system of an automotive vehicle embodying the subject matter of this invention. The heater 23 is mounted on the passenger side of the dash 24 in a conventional manner, and the air separating tank 15 for convenience and conservation of room under the cowl is mounted on the engine side of the dash. The inlet pipe 16 of the tank 15 is shown connected to the cylinder head 25 on the pressure side of the engine water pump 26. As previously mentioned water then enters the separating tank 15 at a tangential opening and centrifugally separates itself from any entrapped air through the spirally downwardly path assumed by the fluid flow. From the tangential outlet pipe 17, air-free water flows through the heating device 23 and out the discharge pipe 14 back to the suction side of the water pump. In this showing air by-pass tube 20 extends from the top of the tank 15 and is connected to the inlet or suction side of the pump 26, whereby an aspirator effect is created at the outlet of tube 20 so as to remove air separated from the water in tank 15 and accumulated in the dome-like top thereof. Alternatively, as shown by dotted lines 20', the air by-pass tube 20 may be joined at the outlet end with the upper tank of the car radiator if desired. In this hook-up the tube 20 would be above the water level in the top tank and in a region of atmospheric pressure due to the venting afforded by the conventional overflow tube incorporated therein. The requisite amount of suction would be available at this point because of the relatively lower value of the atmospheric pressure in relation to the pressure existing in the fluid circuit through the heater.

Since many changes can be made in the formal arrangement and combinations of parts without departing from the spirit and broad scope of this invention, it is not the intention to be limited to the specific construction and modification shown, but to include all possible modifications fairly

within the scope of this invention and limited only by the appended claims.

What I claim is:

1. The combination with a hot water heater core having header tanks at the ends thereof with which supply and discharge pipes are connected, respectively, of a tank for separating air from water for the supply pipe of said heater core, comprising inlet and outlet pipes extending from adjacent the upper and lower portions of said air separating tank, respectively, and an air venting tube extending from the upper portion of said tank to the interior of said heater discharge pipe substantially on the axis thereof and facing in the direction of fluid flow. 15

2. The combination with a hot water heat-exchange core having a header tank at either end thereof with which a supply and discharge pipe are connected, respectively, of an air separating means comprising a tank having a tangentially arranged inlet and outlet in communication with the upper and lower portions thereof, respectively, said air separating tank member adapted to be connected in series with said heat-exchange core supply pipe, and a relatively small air by-pass tube extending from the upper portion of said air separating tank and in communication with the said heat exchange core discharge pipe substantially on the axis thereof and facing in the direction of fluid flow. 30

3. The combination with a hot water heat-exchange core having top and bottom header tanks and discharge and supply pipes leading therefrom, respectively, of a cylindrical tank having inlet and outlet pipes in fluid communication with the tank adjacent the top and bottom portions thereof and serially connected to said heat exchanger supply pipe, and a by-pass pipe shunted between the uppermost portion of said cylindrical tank and the discharge pipe of said heat exchanger substantially on the axis thereof and in the direction of fluid flow, whereby air is delivered through said by-pass pipe and air-free fluid delivered to said heat exchange core supply pipe. 45

4. A water gurgle eliminator for a hot water heater core for the passenger compartment of a motor vehicle, comprising in combination a heat-exchange core having supply and discharge pipes connected therewith, an air-separating tank including inlet and outlet pipes tangentially joined to said tank adjacent the upper and lower portions thereof, respectively, said tank inlet and outlet pipes connected in series in said heater core supply pipe, and an air vent conduit shunted between the uppermost portion of said tank and said heater core discharge pipe substantially on the axis thereof and disposed in the direction of fluid flow. 60

5. In a heat exchange core of the hot water type with which are connected supply and discharge pipes, means to remove air from said supply pipe and by-pass the same to said discharge pipe, comprising a tank member having inlet and outlet pipes serially connected in said supply pipe and a by-pass tube extending from the uppermost portion of the tank to the interior of said discharge pipe substantially on the axis thereof and facing in the direction of fluid flow, and means for creating an aspirating effect in proximity to the discharge outlet of said by-pass tube. 65
